United States Patent Office.

J. D. WEST, OF NEW YORK, N. Y.

Letters Patent No. 99,381, dated February 1, 1870.

IMPROVEMENT IN LIGHTNING-RODS.

The Schedule referred to in these Letters Patent and making part of the same.

Be it known that I, J. D. WEST, of the city, county, and State of New York, have invented a new and improved Mode of Constructing Lightning-Rods; and I do hereby declare that the following is full and sufficient description thereof, reference being had to the accompanying drawings, and to the letters of reference marked thereon.

The nature of my invention consists in preparing a four-square rectangular tube, of copper or other metal, by drawing it through suitable dies arranged for that purpose, and in suitable lengths for convenient working.

The several lengths are fastened together by means of a solid square rod or plug, received into the two contiguous ends of the sections or lengths of the lightning-rod. This plug may be one, two, or more inches in length.

To enable others skilled in the art to make and use my invention, I will proceed to describe its construction and operation.

In the drawing—

Figure 1, A, represents a section of lightning-rod, and B represents the plug, which is to connect the two sections of the rod together.

Figure 2 represents a perspective view of a section of the tube and the plug.

My lightning-rod is best constructed of copper-tubing, drawn as a wire through square dies of any length that may be easily worked, and may be put up in any direction convenient for protecting a building.

The plug B is inserted one-half its length into each of the contiguous ends of the sections of the lightning-rod.

Near each end of the plug, and also at an exact distance from the flush ends of the sections of the tube, is a depression, b, in the side of the plug, made by a punch or other suitable instrument; and after the plug and the sections are put together, a corresponding depression, b', is made in each section of the square tube exactly over the depressions in the plug, which hold the sections firmly together. This plug may have fluted sides, so as to allow the passage of water or other fluid.

What I claim as my invention, and desire to secure by Letters Patent, is—

A lightning-rod, constructed in sections of square metallic tubes, and connected by means of the square plug, fastened substantially as described.

J. D. WEST.
